SEALED BEAM HEADLIGHT MOUNTING

Norbert P. Worden, Detroit, Mich., assignor to C. M. Hall Lamp Co., Detroit, Mich., a corporation of Michigan

Application April 20, 1955, Serial No. 502,680

6 Claims. (Cl. 240—41.5)

This invention relates to lamp mountings, and is exemplarily embodied in a housing for a sealed-beam type head lamp.

In the presently conventional practice, head lamp assemblies comprise a housing or body portion adapted to be mounted on the automobile, a bowl-shaped mounting ring adjustably secured to the body portion, and a sealed-beam unit retained in position in the mounting ring by an annular member known in the trade as a bezel or door. This bezel is customarily secured to the mounting ring by screws engaging aligned apertures in a plurality of overlying pairs of projections on the door and the mounting ring.

Since the external diameter of the mounting ring is substantially the same as the internal diameter of the adjacent portion of the housing, it is necessary to deform the periphery of the housing to provide a series of inner depressions or cavities, with corresponding outer protuberances, to provide clearance for those projections and screws. As a consequence, the adjusting screws may be recessed into the depressions in the housing and, depending upon the adjusted position of the mounting ring relative to the housing, may be so tilted relative to the lamp axis as to render them difficult of tightening and of removal for lamp replacement, particularly when the housing itself is recessed to a substantial degree in the automobile's fender. Further, the protuberances (normally 5 in number) on the outer periphery of the housing necessitate a fender cut-out of involved configuration.

The objects of this invention are to improve the rigidity and stability of lamp mountings, to simplify the initial mounting of lamp housings on automobiles and to simplify the replacement of lamps in their housings.

The manner of accomplishment of the foregoing objects, and other objects of the invention, will be perceived from the following detailed description of an embodiment of the invention when read with reference to the accompanying drawings in which:

Figure 1 is a front elevational view of a head lamp assembly embodying the principles of the present invention;

Fig. 2 is a sectional view taken substantially along the line 2—2 of Fig. 1;

Fig. 3 is a sectional view taken substantially along the line 3—3 of Fig. 1;

Fig. 4 is a sectional view taken substantially along the line 4—4 of Fig. 1; and

Fig. 5 is a sectional view taken substantially along the line 5—5 of Fig. 1.

Referring first to Figs. 1 and 2 of the drawings, the lamp assembly comprises a generally bowl-shaped body member 10 having a rear circular cylindrical portion 12 and a forward cylindrical portion 14 which is larger than the rear portion 12 and which is joined thereto by an annular flange 16. At the line of junction between the rear portion 12 and the flange 16, an inwardly extending fillet 18 of substantial radius is formed to establish a bearing surface.

2

A generally bowl-shaped mounting ring 20 is seated within the lamp housing 10 and is provided with a plurality of circumferentially spaced ridges 22 adapted to engage the bearing surface 18 of the body 10 in the well known manner. At its forwardmost edge, the mounting ring 20 is curved outwardly and reversely to form a flange 24 and is then again curved outwardly to form a lip 26.

To retain the mounting ring 20 seated within the body 10, one end of each of a pair of interjoined springs 30 (Fig. 1) is attached to an individual clip 32, integral with the mounting ring 20, and the point of interjunction of the two springs 30 engages a retaining lug 34 (Fig. 3) affixed to the forward portion 14 of the body 10. A slotted lug 38 (Figs. 1 and 2) is provided at each of two points around the periphery of the lip 26 of the mounting ring 20 and each of these lugs 38 is engaged between the head 40 and shoulder 42 (Fig. 2) of an adjusting screw 44 which engages a nut 46 retained in position relative to the forward portion 14 of the body 10 by means of a lug 48.

In order to form cavities 50 to accept each of the adjusting screws 44, a protuberance 52 is formed at each of two points along the surface of the forward portion 14 of the body 10. These protuberances 52 are preferably so formed that the surface 14 remains cylindrical, but departs from circularity at these two points. During adjustment, the ridges 22 on the mounting ring 20 remain in engagement with the bearing surface 18 on the body 10 so that the mounting ring 20 essentially tilts or rotates, 30 with the ridges 22 sliding upon the bearing surface 18.

A lamp 56 is seated within the mounting ring 20. Lamp 56 may be a bulb-reflector-lens assembly or, preferably, a sealed-beam unit, in either case being provided with an annular lip 58 by means of which the unit may be retained in position. Lamp 56 is retained in position by an annular bezel 60, also commonly labeled a door by the trade. The surface of the bezel 60 is primarily circular cylindrical, but it is provided with an inwardly turned flange 62 adapted to engage the lip 58 of the lamp 56 throughout its length, as may best be seen in Fig. 4 of the drawings.

At a plurality of points around its periphery, exemplarily three, a strip of the bezel material 60 is rolled from the rear edge of the bezel backwardly upon itself 45 to form a sleeve 66 (Figs. 1, 4 and 5), the inner surface of which serves as a bearing for the shank portion of a spring steel clip 68. Each of the spring clips 68 is provided with two arms which diverge from one another as they extend rearwardly of the total assembly, and each 50 of those arms terminates in a hook portion 70. When the lamp 56 is assembled to the mounting ring 20, with the bezel 60 in place, the hook portions 70 of the spring clips 68 extend behind and under the lip 26 of the mounting ring 20 so as tightly to secure the bezel 60, and hence 55 the lamp 56, to the mounting ring 20.

In order to replace the lamp 56, a screwdriver or other similar elongated thin-edged tool is inserted from the front of the assembly into a position abutting successive ones of the hook portions 70 and intermediate the legs 60 of the spring clip 68 and the bezel 60 and flange 24. A simple prying operation will then readily release each of the hook portions 70 from its engagement with the lip 26 so that the bezel 60 and the lamp 56 may be removed. When the new lamp 56 is inserted in the mounting ring 20 and the bezel replaced, the spring clips 68 may be restored to their shown position by employing a screwdriver to lift and force the hook portions 70 over the lip 26. These operations may readily be performed even though the mounting ring 20 has been tilted to a very substantial angle by means of the adjusting screws 44 and even though the entire lamp assembly is very substantially recessed within the fender of the automobile with which

the unit is associated. Further, the employment of clips 63 obviates the possibility of the bezel 60 becoming loose during use, contrary to the experience when screw fastening means are employed.

As may best be seen in Fig. 4 of the drawings, the diameter of the inner surface of the forward portion 14 of the body 10 is normally and preferably the same as the diameter of the outer edge of the lip 26 on the mounting ring 20. As a consequence, in the prior practice a plurality of protuberances additional to protuberances 52 had to be provided on the periphery of the forward portion 14 of the head lamp 10 to accept the screws and flanges which were employed to assemble the prior counterpart of the bezel 60 with the prior counterpart of the mounting ring 20, complicating the forming operations upon the body 10 and complicating the configuration of the cut-out in the automobile's fender into which the body 10 must fit. By virtue of the low silhouette of the clips 63 employed in the present construction, no such additional protuberances are necessary. While it will be noted that the clips 63 do lie outside of the inner surface of the forward portion 14 of the body 10 when the apparatus is positioned as shown in Fig. 4, these clips 63 will in fact amply clear the under surface of the forward portion 14 when the mounting ring 20 is tilted during adjustment since, as before noted, the mounting ring rotates during adjustment so that as any clip 63 is moved rearwardly, it pursues an essentially arcuate course which causes it to pass beneath and within the forward portion 14 of the body 10. Additionally, the clearance is adequate so that a screwdriver may be readily inserted and so that the hook portions 70 may be lifted out of engagement with the lip 26 even though those hook portions 70 are underlying and in spaced proximity to the inner surface of the forward portion 14.

While it will be apparent that the embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. In a lamp assembly, a body, a mounting ring movably seated in said body and having an external annular lip, means including said lip for retaining said mounting ring in said body, a lamp unit seated in said mounting ring, a bezel having a circular cylindrical surface portion and a lip engaging said lamp unit, and a plurality of spring clips mounted on said bezel and having hook portions engageable with said external annular lip on said mounting ring, said bezel securing said lamp unit to said mounting ring, said spring clips serving as the sole means for securing said bezel to said mounting ring so that said bezel can be separated from said mounting ring by disengaging said clips.

2. In a lamp assembly, a body, a mounting ring movably seated in said body and having an external annular lip, a lamp unit seated in said mounting ring, a bezel having a circular cylindrical surface portion and a lip engaging said lamp unit, a plurality of spring clips having hook portions engageable with said external annular lip on said mounting ring for connecting said bezel to said mounting ring, and means for rotatably mounting each of said spring clips on said bezel, each of said clips being rotatable while said bezel is in position with respect to said mounting ring between a position in which said hook portion is engaged with said external annular lip and a position in which said hook portion is spaced from said external annular lip, said bezel securing said lamp unit to said mounting ring, said spring clips serving as the sole means for securing said bezel to said mounting ring so that said bezel can be separated from said mounting ring by disengaging said clips.

3. In a lamp assembly, a body, a mounting ring movably seated in said body and having an external annular

lip, a lamp unit seated on said mounting ring, a bezel having a circular cylindrical surface portion and a lip engaging said lamp unit, a plurality of spring clips each comprising a shank portion, two diverging leg portions and a hook portion at one end of each leg portion, said hook portions being engageable with said external annular lip on said mounting ring for connecting said bezel to said mounting ring, and a plurality of tubular sleeves integral with said bezel and each rotatably supporting the shank portion of an individual one of said spring clips, each of said clips being rotatable while said bezel is in position with respect to said mounting ring between a position in which said hook portion is engaged with said external annular lip and a position in which said hook portion is spaced from said external annular lip, said bezel securing said lamp unit to said mounting ring, said spring clips serving as the sole means for securing said bezel to said mounting ring so that said bezel can be separated from said mounting ring by disengaging said clips.

4. In a lamp assembly, a body having a forward tubular portion the major portion of the inner surface of which is circular cylindrical, a mounting ring tiltably seated in said body and having an outer annular lip, the outer diameter of said outer annular lip being substantially equal to the diameter of said circular cylindrical inner surface portion of said body, a lamp unit seated in said mounting ring, a bezel having a circular cylindrical surface portion and a lip engaging said lamp unit, and a plurality of spring clips mounted on said bezel and having hook portions engageable with said outer annular lip on said mounting ring, portions of said spring clips lying within said inner circular cylindrical surface when said mounting ring is appropriately tilted relative to said body.

5. In a lamp assembly, a hollow body having a rear portion and a front portion, both of said portions having cylindrical outer and inner surfaces, the major portion of the outer and inner surfaces of said forward portion being circular cylindrical, a flange interjoining said front and rear portions, the junction between said flange and said rear portion having an arcuate cross section, a mounting ring seated in said body and having a plurality of ridges engageable with said arcuate cross-section junction, means for selectively tilting said mounting ring relative to said body, an outer annular lip on said mounting ring, the outer diameter of said annular lip being substantially equal to the diameter of said inner circular cylindrical surface, a lamp unit seated in said mounting ring, a bezel having a circular cylindrical surface portion and a lip engaging said lamp unit, and a plurality of spring clips mounted on said bezel and having hook portions engageable with said outer annular lip on said mounting ring, portions of said spring clips lying within said inner circular cylindrical surface when said mounting ring is appropriately tilted relative to said body.

6. In a lamp assembly, a hollow body having a rear portion and a front portion, both of said portions having cylindrical outer and inner surfaces, the major portion of the outer and inner surfaces of said forward portion being circular cylindrical, a flange interjoining said front and rear portions, the junction between said flange and said rear portion having an arcuate cross section, a mounting ring seated in said body and having a plurality of ridges engageable with said arcuate cross-section junction, means for selectively tilting said mounting ring relative to said body, an outer annular lip on said mounting ring, the outer diameter of said annular lip being substantially equal to the diameter of said inner circular cylindrical surface, a lamp unit seated in said mounting ring, a bezel having a circular cylindrical surface portion and a lip engaging said lamp unit, a plurality of spring clips each comprising a shank portion, two diverging leg portions and a hook portion at one end of each leg portion, said hook portions being engageable with said outer annular

lip on said mounting ring, and a plurality of tubular sleeves integral with said bezel and each rotatably supporting the shank portion of an individual one of said spring clips.
